[57] CLAIM

The ornamental design for a bedpan, as shown and described.

DESCRIPTION

FIG. 1 is a front perspective view of a bedpan embodying my new design;

FIG. 2 is a rear perspective view thereof;

FIG. 3 is a top plan view;

FIG. 4 is a front elevation;

FIG. 5 is a rear elevation;

FIG. 6 is a side elevation;

FIG. 7 is a bottom plan view;

FIG. 8 is a longitudinal sectional view on line 8—8 of FIG. 3; and

FIG. 9 is a cross-sectional view on line 9—9 of FIG. 3; The side opposite to that shown in FIG. 6 is a mirror image thereof.

FIG. 1

FIG. 2

FIG. 6

FIG. 7

FIG. 8

FIG. 9
